UNITED STATES PATENT OFFICE.

ISAAC J. SALTZER, OF PRESCOTT, PENNSYLVANIA, ASSIGNOR OF ONE-HALF
TO JOHN G. ECKERT, OF SAME PLACE.

SASH-FASTENER.

SPECIFICATION forming part of Letters Patent No. 297,953, dated April 29, 1884.

Application filed February 14, 1884. (No model.)

To all whom it may concern:

Be it known that I, ISAAC J. SALTZER, a citizen of the United States, and a resident of Prescott, in the county of Lebanon and State of Pennsylvania, have invented certain new and useful Improvements in Sash-Fasteners; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of part of a window-casing from the inside, showing the arrangement of my improved sash-fastener. Fig. 2 is a perspective view of one of the fasteners with its box removed from the window-casing. Fig. 3 is a longitudinal sectional view of the same. Fig. 4 is a perspective view of the box and spring with the catches removed; and Fig. 5 is a perspective detail view of the two engaging catches, showing them separated from each other.

Similar letters of reference indicate corresponding parts in all the figures.

My invention has relation to sash fasteners or holders adapted for holding the upper and lower sashes of a window in their proper position in the window frame or casing; and it consists in the improved construction and combination of parts of a duplex catch or fastener, as hereinafter more fully described, and particularly pointed out in the claim.

In the accompanying drawings, A denotes the window-casing, which has the usual ways, B, for guiding the motion of the sashes, (shown at C.)

My improved fastener or holder is composed of a metallic box, D, having ears E, for fastening it by screws or nails in the window-casing, which is cut out or recessed for the insertion of the box. In the bottom of this box is placed a removable spring, F, bent to form a bulge, f, and at each end of the box is a cross-bar, G, upon which the catches are hung. The latter (two in number) consist each of a wedge-shaped piece of metal cut off or recessed at one side to form a wedge-shaped shoulder or offset. H denotes one of these pieces, and

I the wedge-shaped shoulder or offset, the width or thickness of which is half of that of the body H. At one end is a transverse groove or recess, h, and the rounded under side, i, of the parts H I will, when the catches are properly inserted into the box, bear against the bulging part of spring F, as will appear more clearly by reference to Fig. 3 of the drawings. The corresponding catch is constructed in precisely the same manner, consisting of a wedge-shaped body, H', having a slightly rounded under side, i', bearing against the spring F, and having the wedge-shaped shoulder or offset I' on one side, formed by cutting away one side of the part H' to half its thickness. One of the catches is provided with a projection, K, having a finger-knob, L, for operating the device. The catches H I and H' I' are inserted into the box D by slipping their hooked ends formed by the transverse grooves or recesses h and h' around the cross-bars G at opposite ends of the box, in which position it will be seen that the projecting wedge-shaped end of one of the catches will bear against the wedge-shaped offset or shoulder I of the other catch, and vice versa, both the catches being actuated by the spring F, so as to cross and project their points in opposite directions out of the box. The stiles or sides of the sliding sashes are provided with plates M, having projections or studs N, adapted to engage the projecting ends of the spring-actuated catches, and placed at such a distance apart as to readily engage both catches at the same time. By depressing the knob or thumb-piece L, which projects to one side of the window-casing, so as to be readily accessible from the inside, the projecting catches will be depressed by compressing the bulging spring F, so as to draw the points back from plate M flush with the face of the box, and thereby permit the sash to move up or down. When, however, the thumb-piece L is let go, spring F will force the free ends of the catches, which cross each other, out of the box, so as to engage with their points the projections N on plate M. If the spring F should get broken or otherwise become useless, it may readily be removed by removing the two overlapping catches from the box, which may readily be

done by slipping them off of the cross-bars G G, into which they may as readily be reinserted after a new spring has been placed in the bottom of the box.

5 It will be seen that no screws or other fastenings are required for connecting the several parts of my improved sash-holder, and that its construction and combination of parts are such that it cannot readily get out of order.

10 Having thus described my invention, I claim and desire so secure by Letters Patent of the United States—

15 In a sash holder or fastener, the combination of the box having the cross-bars at opposite ends, the removable bulging spring, the two

bolts or wedge-shaped catches hung removably upon the cross-bars at opposite ends of the box, crossing each other with their free ends and bearing against the spring at their point of intersection, and the thumb-lever projecting 20 from the side of one of the wedge-shaped catches, as and for the purpose shown and set forth.

In testimony that I claim the foregoing as my own I have hereunto affixed my signature 25 in presence of two witnesses.

ISAAC J. SALTZER.
